Patented Dec. 29, 1931

Des. 85,892

UNITED STATES PATENT OFFICE

JOHN M. SMITH, OF WASHINGTON, DISTRICT OF COLUMBIA

DESIGN FOR A LETTER SHEET OR SIMILAR ARTICLE

Application filed July 9, 1931. Serial No. 40,471. Term of patent 7 years.

To all whom it may concern:

Be it known that I, JOHN M. SMITH, a citizen of the United States of America, residing at Washington, in the District of Columbia, have invented a new, original, and ornamental Design for a Letter Sheet or Similar Article, of which the following is a specification, reference being had to the accompanying drawing, forming a part hereof.

The figure of the drawing is a plan view of a letter sheet or similar article showing my design.

I claim:

The ornamental design for a letter sheet or similar article, as shown.

JOHN M. SMITH.
